US0D1075157S

(12) **United States Design Patent** (10) **Patent No.:** **US D1,075,157 S**
(45) **Date of Patent:** **** May 13, 2025**

(54) **BACK SCRATCHER**

(71) Applicant: **Qunying Jiang**, Shenzhen (CN)

(72) Inventor: **Qunying Jiang**, Shenzhen (CN)

(**) Term: **15 Years**

(21) Appl. No.: **29/954,576**

(22) Filed: **Jul. 27, 2024**

(51) **LOC (15) Cl.** **28-99**

(52) **U.S. Cl.**

USPC **D28/91.2**

(57) **CLAIM**

The ornamental design for a back scratcher as shown and described.

DESCRIPTION

FIG. 1 is a rear, right and top perspective view of a back scratcher showing my design;

FIG. 2 is a front, left and bottom perspective view thereof;

FIG. 3 is a front elevation view thereof;

FIG. 4 is a rear elevation view thereof;

FIG. 5 is a left-side elevation view thereof;

FIG. 6 is a right-side elevation view thereof;

FIG. 7 is a top plan view thereof; and,

FIG. 8 is a bottom plan view thereof.

The broken lines are included for the purposes of illustrating portions of the back scratcher that form no part of the claimed design.

1 Claim, 8 Drawing Sheets
